UNITED STATES PATENT OFFICE.

DAVID T. MAY, OF NEW YORK, N. Y., ASSIGNOR TO WESTERN ELECTRIC COMPANY,
INCORPORATED, OF NEW YORK, N. Y., A CORPORATION OF NEW YORK.

PROTECTIVE DEVICE.

1,319,719.

Specification of Letters Patent.

Patented Oct. 28, 1919.

Application filed January 18, 1918. Serial No. 212,471.

To all whom it may concern:

Be it known that I, DAVID T. MAY, a citizen of the United States, residing at New York, in the county of New York, State of New York, have invented certain new and useful Improvements in Protective Devices, of which the following is a full, clear, concise, and exact description.

This invention relates to devices for protecting electrical circuits from abnormal voltages, and more particularly to lightning arresters which comprise a discharge gap in a vacuum.

One requisite of an arrester for use in connection with telephone and like circuits is that its discharge or breakdown voltage shall be somewhat less than 550 volts D. C., that is to say, when subjected to such a voltage, the device will permit the discharge of electricity across its gap, thus providing a shunt past the apparatus to be protected. As is well known, the discharge or breakdown voltage of a gap decreases as the air pressure is reduced until a certain critical pressure is reached, after which a further reduction in pressure causes the rapid rise in the minimum voltage that can overcome the resistance of the gap. It is therefore desirable to maintain at the gap a degree of vacuum 30 as near as practicable to the critical pressure for the length of the gap selected.

A further requirement to be met is that the high-voltage protective value of the arrester should be high; that is to say, high-voltage, high-frequency currents will pass through the arrester rather than through the apparatus to be protected. This high-voltage protective value is customarily denoted in terms of the equivalent spark gap 40 or the E. S. G. of the arrester, that is, the length of the gap in air between two electrodes in parallel with the arrester gap which will be refused by high-voltage, high-frequency discharges in favor of the arrester 45 gap. Evidently, the smaller the equivalent spark gap of an arrester, the greater will be its protective value. As in the case of the discharge voltage, there is, for a given spacing of selected electrodes, a critical pressure for 50 the equivalent spark gap at which it has a minimum value, increasing therefrom whether the pressure be increased or decreased. This critical pressure does not, however, as a rule, coincide with the breakdown voltage critical pressure, the former

being appreciably higher than the latter. As a consequence, the actual pressure in vacuum arresters is usually somewhere between the two critical pressures, the actual breakdown voltage and the actual equivalent spark gap 60 being both higher than their minimum values.

It is an object of this invention to provide a vacuum arrester in which the difference between these two critical pressures is rendered as small as possible, and in which, therefore, the compromise intermediate pressure at which the arrester is used needs to differ but little from either critical pressure. I have discovered that this result may be 70 obtained by maintaining a magnetic field longitudinally across the gap between the electrodes.

The means whereby this is accomplished, and further advantages resulting therefrom, 75 will be apparent from the following detailed description taken in connection with the accompanying drawings in which Figure 1 illustrates one form of a vacuum arrester embodying this invention, the front of the 80 container being broken away; Fig. 2 is a view partly in cross-section of a modified arrester; and Fig. 3 is a chart graphically showing the phenomena involved.

In the arrester shown in Fig. 1 there is 85 provided an evacuated container 2, through opposite ends of which are sealed leading-in conductors 4. A plate electrode 6 of brass or other suitable metal, is connected to the inner end of each conductor, the two electrodes facing each other and being separated by a sheet of insulating material 8, such as mica which is shorter than the electrodes, so as to leave at each end a discharge gap 10. The electrodes 6 are held in fixed spaced parallel relation by means of the insulating sheet 8 and a pair of clamping plates 12 connected by bolts 14 and separated from the electrodes by insulation 16. On the rear side of each electrode is mounted a permanent 90 magnet 18 having its ends curved to bring its pole faces against the ends of the electrode, to which it is secured by screws 20 passing through ears 22 on the ends of the electrode. The magnets are so arranged 95 that the north pole of one is opposite the south pole of the other, and a magnetic field is therefore maintained across each discharge gap.

Other arrangements of electrodes and mag- 110

nets may be employed, that above described being selected because the brass plates 6 form better electrodes than would the faces of the steel magnets; moreover, such electrodes will 5 take almost all of a discharge and thus prevent the discharge from demagnetizing the magnets 18. Centering washers 24 mounted at opposite ends of the assembled electrodes and magnets prevent lateral displacement 10 thereof.

In the modification shown in Fig. 2 the construction is the same as that above described, except that the electrodes 7 have their ends 9 out-turned to provide comparatively wide discharge gaps 11, while the insulating separator 15 is divided into two spaced parts whereby there is afforded a central discharge gap 13 substantially shorter than the gaps 11. The normal pressure in the container will be so close to the critical pressure of the gaps 11, that the discharge will take place across one or both of these gaps; while, if because of leakage or otherwise, the gas pressure rises considerably above the critical pressure of the gaps 11, the discharge will not be prevented but will take place across the gap 13, since the critical pressure rises as gap length decreases. In this form, by the use of the 25 magnets, the normal pressure of the device may, as explained above, be brought much closer to the critical pressure of the gaps 11, and the certainty of operation of the 30 arrester under high voltages will be increased.

The chart of Fig. 3 shows graphically the equivalent spark gap and breakdown values corresponding to different pressures for an arrester having a discharge gap of one 40 thirty-second of an inch, which has been found to be the most satisfactory length in arresters of this general type. As shown thereon, the discharge or breakdown voltage critical pressure is about four millimeters of mercury, while the equivalent spark gap critical pressure is approximately twenty-five millimeters of mercury when the gap is unmagnetized. Assuming that the actual compromise pressure selected is 45 that indicated by the ordinate A B, namely, fifteen millimeters of mercury, which corresponds to a satisfactory E. S. G. value, namely, about twenty-four thousandths of an inch, it will be seen that the breakdown 50 voltage is nearly 500 volts.

When a magnetic field is produced longitudinally across the gap, the E. S. G. values for the given length of the gap are lowered, as indicated by the curve C D, the 55 equivalent pressure being substantially lowered to about fifteen millimeters of mercury. As a consequence of the reduced pressure in the gap containing the electrodes, the equivalent spark gap pressure is reduced, the breakdown voltage being substantially unchanged;

or it may be reduced to a pressure corresponding to the equivalent spark gap voltage used with the unmagnetized gap, thus reducing the breakdown voltage; or an intermediate pressure may be chosen. The 70 second course will generally be followed, as it is usually most desirable to reduce the breakdown voltage, the protection against high voltages by present arresters having unmagnetized gaps being considered sufficient for most installations. Therefore, in the example given, a pressure of about six millimeters of mercury, as indicated by the broken line ordinate C D, will generally be used, at which pressure both the discharge 75 voltage and the equivalent spark gap have desirable values.

What is claimed is:

1. In a protective device for electric circuits, a partially evacuated container, 85 spaced electrodes providing a discharge gap in said container, and means reducing the equivalent spark gap value of said discharge gap below the value normally corresponding to the spacing of said electrodes at the gas 90 pressure in said container.

2. In a protective device for electric circuits, a partially evacuated container, a pair of spaced electrodes in said container spaced to provide a discharge gap having 95 a selected breakdown voltage, and means reducing the equivalent spark gap value of said discharge gap below the value normally corresponding to the spacing of said electrodes at the gas pressure in said container. 100

3. In a protective device for electric circuits, a partially evacuated container, a pair of spaced electrodes in said container, and means within said container for producing 105 a magnetic field between said electrodes.

4. In a protective device for electric circuits, a partially evacuated container, a pair of spaced electrodes in said container, and means within said container for producing 110 between said electrodes a magnetic field extending in the direction of discharge between said electrodes.

5. In a protective device for electric circuits, a partially evacuated container, a pair 115 of plate electrodes in said container facing each other in spaced relation, and a magnet mounted on the rear side of each electrode with its pole faces adjacent the ends thereof and opposed to unlike pole faces on the 120 magnet on the other electrode.

6. In a protective device for electric circuits which comprises two alternate discharge gaps, means producing a magnetic field at one of said gaps. 125

7. In a protective device for electric circuits comprising two alternative discharge gaps of different lengths, means producing a magnetic field at the longer gap.

8. In a protective device for electric cir- 130

cuits, a partially evacuated container, a pair of plate electrodes in said container facing each other in spaced relation, the end portions of said electrodes being spaced farther apart than their central portions, whereby said end portions and central portions form discharge gaps of different lengths, and a magnet mounted on the rear side of each

electrode with its pole faces adjacent the ends thereof and opposed to unlike pole 10 faces on the magnet on the other electrode.

In witness whereof, I hereunto subscribe my name this 12th day of January A. D., 1918.

DAVID T. MAY.
